UNITED STATES PATENT OFFICE.

CHARLES HELLSTROM, OF HARTFORD, CONNECTICUT, ASSIGNOR TO UNDERWOOD TYPE-WRITER COMPANY, OF NEW YORK, N. Y., A CORPORATION OF NEW JERSEY.

TYPE-WRITING MACHINE.

970,708.

Specification of Letters Patent. Patented Sept. 20, 1910.

Application filed January 22, 1908. Serial No. 412,119.

To all whom it may concern:

Be it known that I, CHARLES HELLSTROM, a citizen of the United States, residing in Hartford, in the county of Hartford and State of Connecticut, have invented certain new and useful Improvements in Type-Writing Machines, of which the following is a specification.

This invention relates to the paper feeding devices of writing machines, particularly to those of the front strike variety, in which a ribbon is vibrated up and down to cover the printing point at the type strokes.

Much difficulty has been experienced in guiding stiff cards around the cylindrical platen, because the cards tend constantly to bulge out from the platen and to catch in the ribbon, and also to catch upon the type guide. Moreover, it has been found usually impracticable to write upon the card near its top and bottom edges, which are found especially liable to stand away from the platen, and which hence are not properly supported or backed to receive the type blows.

The object of the present invention is to provide means for controlling the card, so as to avoid these objections, and enable writing to be done along its top and bottom edges.

My improvements are illustrated as applied to an Underwood front strike writing machine, in which a cylindrical platen is revolvably mounted upon a platen frame, the latter supported upon a traveling carriage. I mount upon the framework of the machine two card guides, each consisting of a thin yielding plate and extending up in contiguity to the platen well beyond the printing line on the platen, one on each side of the ribbon vibrator and close thereto, so as to hold firmly against the platen all portions of the card which are in the immediate vicinity of the printing point at any time. These guides hold both top and bottom edges close against the platen, so that the card is well supported and may be written along both its top and bottom edges. Each of the card guides also has on each of its sides a forwardly flaring lip adapted to turn the side edge of the card toward the platen as the latter moves longitudinally, so that liability of the edge of the card catching upon the guides is prevented. Owing to the prox-

imity of the guides to each other, the writing can be carried close to either side edge of the card, since when the card moves to the right or left past either guide, the other guide holds the card against the platen, while the flaring lip enables the first guide to regain control of the card at the opposite movement of the platen. I also provide a pair of rolls to run upon the platen immediately above the tops of the guides, to control the card after it has advanced beyond the usual pressure rolls, so that writing may be continued right down to the bottom edge of the card. These rolls are adjustable independently of each other along the platen. A key is mounted upon the platen frame and connected to the rolls to release them, the construction being such that the rolls will stand away from the platen without further attention from the operator, so that the leading edge of the advancing card may pass between the rolls and the platen; whereupon, the key may be lifted to restore the rolls to active positions, and the rolls then serve to hold the card smoothly against the platen, and to advance the same after it has advanced beyond the control of the usual rolls mounted under the platen.

In the accompanying drawings, Figure 1 is a sectional side elevation of a platen frame of an Underwood typewriting machine, showing my improvements applied thereto. Fig. 2 is a perspective view of a card guide. Fig. 3 is a front elevation of parts seen at Fig. 1. Fig. 4 illustrates the manner in which a roll-releasing key is held in depressed or abnormal position. Fig. 5 is a fragmentary view similar to Fig. 1, but showing the card holding rolls as swung slightly away from the platen, to form a temporary guard or guide for the card as it is inserted in the machine. Fig. 6 is a plan to illustrate the positions of the card guides back of the usual ink ribbon.

Types 1 strike through a ribbon 2 upon the front side of a platen 3, which is journaled by means of an axle 4 in the ends 5 of a platen frame, which comprises a paper shelf 6. A gage 7 for the side edge of the card is attached to the paper shelf 6. The card 8 is carried around the under side of the platen by the usual rear and front pressure rolls 9 and 10. As it advances up the front sides of the platen, it passes under the

- control of a pair of guides 11, which are attached at their lower ends by means of screws 12 to a type bar segment 13, and extend upwardly and rearwardly to form with 5 the platen a directrix for the leading edge of the card. The card guides extend up beyond the writing or printing line on the platen, Fig. 3, and bear yieldingly against the front of the platen and hold the card 10 firmly thereagainst. These guides are very close to the usual vibrator 2^a, which carries the ribbon 2, so that the leading edge of the card may not catch that portion of the ribbon which stretches across the back of 15 the vibrator, the guides being sufficiently close to the platen to press the leading edge of the card back from the ribbon. Each of the guides has flaring lips 14, 15, upon its sides to direct the side edge of the card 20 toward the platen, so that the platen carriage (a portion of which is seen at 16) may be run backward and forward freely. Each guide is close to the vibrator 2^a, so that when the card has advanced past one guide, 25 it is held by the other, and thus writing may be carried close to the side edges of the card. Each guide is also provided with an upwardly extending flaring lip 17.
- Each guide 11 is provided with an aperture or eye 18, preferably rectangular, and extending for nearly the entire width of the 30 guide. The lower edge 19 of each eye is coincident or in register with the printing line on the platen, and both said lower edges 35 taken together may be made to do duty as a scale to enable the operator to square the leading edge of the card to the writing line, or to adjust any desired line on the card into register with the writing line on the platen.
- 40 Each guide is provided also with graduations 20 in proximity to the edge 19 to register with the type impressions upon the platen, said graduations being at letter space intervals.
- 45 Upon advancing up beyond the guides 11, the leading edge of the card passes between a pair of rolls 21 and the platen 3, Fig. 5, said rolls having been cast off by means of a key 22. The latter is mounted upon one 50 end of a rock shaft 23 journaled at its ends in yokes 24, the latter detachably secured upon the platen frame ends by means of thumb screws 25, which pass down through bases 26 secured to said yokes, and seated 55 upon the tops of the side bars of the platen frame. Along the under side of the rock shaft extends a groove 27, in which fit rolls or keys 28 guided in slots 29 formed in the arms of the yoke 24. Bow springs 30 press 60 the rolls 28 into the groove, and thereby hold the rock shaft in normal position with the key 22 elevated; Fig. 1. When the key 22 is depressed to the Fig. 5 position, the rolls 28 are forced out of the groove 27 and 65 press upon the cylindrical periphery of the

rock shaft, and are hence incapable of turning the latter, so that the rolls 21 stand away from the platen without the necessity of the operator holding down the key 22.

The pressure rolls 21 are supported upon 70 the rock shaft by means of yokes 31 similar to 24 and having keys 32 pressed by springs 33 into the groove 27, so that the yokes and rolls 21 are compelled to swing with the rock shaft. Either yoke 31 may be slid 75 along the shaft independently of the other, or swung up independently as indicated in dotted lines at Fig. 5. The pressure of each roll 21 against the platen 3 may be independently regulated by means 80 of a thumb screw 34 threaded through an ear 35,—that is, attached by screws 36 to the cross bar of the yoke 31. Said screw presses against a yielding arm 37, whose lower end carries the roll 21, and whose 85 upper end is bent at 38 and clamps between the ear 35 and the yoke 31.

In moving up from the printing line, the card goes directly behind the rock-shaft 23, which is right over the front of the platen, 90 so that there is no necessity to flex the card unduly around the top of the platen, which would tend to make its bottom edge bulge out at the printing point, and would usually produce an objectionable permanent set or 95 curve in the card itself.

Having thus described my invention, I claim:

1. In a front strike writing machine having a revoluble platen and a carriage therefor, and a ribbon carrier mounted in front of the platen, a card-holder comprising a pair of yielding guides mounted upon the framework and extending upwardly beyond the printing line and contiguous to the 100 platen, one at each side of the ribbon carrier and close thereto, to prevent the leading edge of the card from catching upon the ribbon; each of said guides being in the form of a plate having an eye whose lower 110 edge coincides with the printing line, said eyes coöperating to enable the operator to adjust any desired line on the card to register with the printing line on the platen.

2. In a front strike writing machine having a revoluble platen and a carriage therefor, and a ribbon carrier mounted in front of the platen, a card-holder comprising a pair of yielding guides mounted upon the framework and extending upwardly beyond 120 the printing line and contiguous to the platen, one at each side of the ribbon carrier and close thereto, to prevent the leading edge of the card from catching upon the ribbon; each of said guides being in the 125 form of a plate having an eye whose lower edge coincides with the printing line, said eyes coöperating to enable the operator to adjust any desired line on the card into register with the printing line on the platen; 130

scale marks being provided on said guides at said lower edges to register with type impressions.

3. In a front strike writing machine having a revoluble platen and a carriage therefor, and a ribbon carrier mounted in front of the platen, a card-holder comprising a pair of yielding guides mounted upon the framework and extending upwardly beyond the printing line and contiguous to the platen, one at each side of the ribbon carrier and close thereto, to prevent the leading edge of the card from catching upon the ribbon; each of said guides being in the form of a plate having an eye whose lower edge coincides with the printing line, said eyes coöperating to enable the operator to adjust any desired line on the card to register with the printing line on the platen; each of said guides having a lip flaring from each of its sides to direct the side edges of the card toward the platen as the latter moves with the carriage.

4. In a front strike writing machine, the combination with a revoluble platen and a platen frame, of a rock shaft journaled at its ends upon the platen frame over the platen and extending along the front of the platen, arms dependent from said rock-shaft and having rolls at their lower ends to run upon the platen, a key on said rock shaft to move said rolls away from the platen, and a spring to cause said shaft to press the rolls against the platen; said spring and rock-shaft being constructed to permit the finger piece to rotate the shaft slightly to a position at which the spring is ineffective to operate the shaft and to hold the rolls mechanically away from the platen to form a temporary guard for the card while the leading edge of the card advances between the rolls and the platen.

5. In a front strike writing machine, the combination with a revoluble platen and a platen frame, of a rock shaft journaled at its ends upon the platen frame over the platen and extending along the front of the platen, arms dependent from said rock-shaft and having rolls at their lower ends to run upon the platen, a key on said rock shaft to move said rolls away from the platen, and a spring to cause said shaft to press the rolls against the platen; said spring and rock-shaft being constructed to permit the finger-piece to rotate the shaft slightly to a position at which the spring is ineffective to operate the shaft and to hold the rolls mechanically away from the platen to form a temporary guard for the card while the leading edge of the card advances between the rolls and the platen; said arms splined to the rock shaft for adjustment therealong.

6. In a front strike writing machine, the combination with a revoluble platen and a platen frame, of a rock shaft journaled at

its ends upon the platen frame over the platen and extending along the front of the platen, arms dependent from said rock-shaft and having rolls at their lower ends to run upon the platen, a key on said rock shaft to move said rolls away from the platen, and a spring to cause said shaft to press the rolls against the platen; said spring and rock-shaft being constructed to permit the finger piece to rotate the shaft slightly to a position at which the spring is ineffective to operate the shaft and to hold the rolls mechanically away from the platen to form a temporary guard for the card while the leading edge of the card advances between the rolls and the platen; said arms splined to the rock shaft for adjustment therealong, and each having independent means for adjusting the pressure of its roll against the platen.

7. In a front strike writing machine, the combination with a revoluble platen and a platen frame, of a rock shaft journaled at its ends upon the platen frame over the platen, arms pendent from said rock shaft and having rolls at their lower ends to run upon the platen, a key on said rock shaft to move said rolls away from the platen, and a spring to cause said shaft to press the rolls against the platen; said arms splined to the rock shaft for adjustment therealong, and each having independent means for adjusting the pressure of its rolls against the platen, comprising an ear secured to said arm, a spring carrying said roll, and a thumb screw to press the spring.

8. In a typewriting machine, the combination with a revoluble platen and a platen frame, of a rock shaft having a longitudinal groove, yokes fixed upon the platen frame ends, the rock shaft being journaled in the yokes, rollers fitting in slots in the yokes and pressed by springs into said groove, roll-carrying arms having yokes hung upon said rock shaft and adjustable therealong and also having rolls pressed by springs into said groove, and a key upon said rock shaft to swing the arm away from the platen and force the first-mentioned rolls out of the groove.

9. In a front strike writing machine having a revoluble platen and a carriage therefor, and a ribbon vibrator mounted in front of the platen, a card-holder comprising a pair of yielding guides mounted upon the framework and extending upwardly beyond the printing line and contiguous to the platen, one at each side of the ribbon vibrator and close thereto, to prevent the leading edge of the card from catching upon the ribbon; and spring-pressed rolls mounted upon the platen frame to bear against the platen directly above said guides.

10. In a front strike writing machine having a revoluble platen and a carriage there-

for, and a ribbon vibrator mounted in front of the platen, a card-holder comprising a pair of yielding guides mounted upon the framework and extending upwardly beyond the printing line and contiguous to the platen, one at each side of the ribbon vibrator and close thereto, to prevent the leading edge of the card from catching upon the ribbon; spring-pressed rolls mounted upon the platen frame to bear against the platen directly above said guides, and a key to throw said rolls slightly away from the platen to serve as temporary guards or guides for the card at its insertion into the machine.

11. In a front strike writing machine having a revolute platen and a carriage therefor, and a ribbon vibrator mounted in front of the platen, a card-holder comprising a pair of yielding guides mounted upon the framework and extending upwardly beyond the printing line and contiguous to the platen, one at each side of the ribbon vibrator and close thereto, to prevent the leading edge of the card from catching upon the ribbon; spring-pressed rolls mounted upon the platen frame to bear against the platen directly above said guides, and a key to throw said rolls away from the platen; means being provided to hold said rolls in released positions.

12. In a front strike writing machine having a revolute platen and a carriage therefor, and a ribbon vibrator mounted in front of the platen, a card-holder comprising a pair of yielding guides mounted upon the framework and extending upwardly beyond the printing line and contiguous to the platen, one at each side of the ribbon vibrator and close thereto, to prevent the leading edge of the card from catching upon the ribbon; spring-pressed rolls mounted upon the platen frame to bear against the platen directly above said guides, and a key to throw said rolls away from the platen; means being provided to hold said rolls in released positions; said rolls being independently adjustable along the platen.

13. In a front strike writing machine having a revolute platen and a carriage therefor, and a ribbon vibrator mounted in front of the platen, a card-holder comprising a pair of yielding guides mounted upon the framework and extending upwardly beyond the printing line and contiguous to the platen, one at each side of the ribbon vibrator and close thereto, to prevent the leading edge of the card from catching upon the ribbon, a rock shaft journaled at its ends

upon the platen frame over the platen and extending along the front of the platen, arms pendent from said rock shaft and having rolls at their lower ends to run upon the platen, a key in said rock shaft to move said rolls away from the platen, and a spring to cause said shaft to press the rolls against the platen.

14. In a typewriting machine, the combination with a revolute platen and a platen frame, of a rock shaft having a longitudinal groove, yokes fixed upon the platen frame ends, the rock shaft being journaled in the yokes, rollers fitting in slots in the yokes and pressed by springs into said groove, roll-carrying arms secured upon said rock shaft and adjustable therealong, and a key upon said rock shaft to swing the arms away from the platen and force the first-mentioned rolls out of the groove.

15. In a front strike writing machine having a revolute platen and a carriage therefor, and a ribbon vibrator mounted in front of the platen, a card-holder comprising a pair of yielding guides mounted upon the framework and extending upwardly beyond the printing line and contiguous to the platen, one at each side of the ribbon vibrator and close thereto, to prevent the leading edge of the card from catching upon the ribbon, and spring-pressed rolls mounted upon the platen frame to bear against the platen directly above said guides; said rolls carried on a rod or shaft extending along the front of the platen, to permit the card to move substantially straight up from the printing point and emerge in a substantially flat condition between the rod and the platen.

16. In a front strike writing machine having a revolute platen and a carriage therefor, and a ribbon vibrator mounted in front of the platen, a card-holder comprising a pair of yielding guides mounted upon the framework and extending upwardly beyond the printing line and contiguous to the platen, one at each side of the ribbon vibrator and close thereto, to prevent the leading edge of the card from catching upon the ribbon, and spring-pressed rolls mounted upon the platen frame to bear against the platen directly above said guides, each of said guides having laterally beveled guards or guides in proximity to said ribbon vibrator to catch the side edges of the card as the carriage moves to and fro.
